UNITED STATES PATENT OFFICE

JAMES E. CONNOLLY, OF BALTIMORE, MARYLAND

SAFETY RAZOR

Application filed February 25, 1931. Serial No. 518,256.

The invention relates generally to razors of the so-called safety type and primarily has for its object to provide a novel razor construction embodying a handle equipped with a resilient vibratory element engaged by the hand of a user of the razor while shaving and active in absorbing shocks incident to the shaving function.

Another object of the invention is to provide in a razor equipped as above stated means to enable adjustment of the position of the vibratory element so that instead of absorbing shocks incident to shaving, the element, by reason of its position and engagement by the hand of a user, will bring about a vibratory movement of the razor head serving to facilitate the shaving act.

A further object of the invention is to provide a novel form of guard plate equipped with teeth having angled faces serving to deflect hairs and to present them to the cutting blade at an angle, thereby cooperating with the vibratory movement of the razor head in assuring a clean shave. The invention also comprehends the arrangement of the teeth in oppositely angled sets whereby to bring about a stretching of the skin which further facilitates the shaving function.

Other objects will in part be obvious and in part be pointed out hereinafter.

To the attainment of the aforesaid objects and ends, the invention still further resides in the novel details of construction, combination and arrangement of parts all of which will be first fully described, then be particularly pointed out in the appended claims, reference being had to the accompanying drawings, in which:

Figure 1 is a side elevation looking toward one end of the head of a razor embodying the invention, parts being broken away and in section;

Figure 2 is a face view of a razor embodying the invention, parts being broken away in section; a modified form of vibratory but-

ton being shown adjusted to impart a vibratory movement to the razor head;

Figures 3, 4 and 5 are detail side elevations of razor handles, each illustrating a modified form of vibratory element mounting, parts being broken away and in section, all said modifications being directed to mountings inside the handle;

Figures 6 and 7 are detail side elevations of razor handles illustrating further modified forms of vibratory elements mounted outside the handles;

Figure 8 is a plan view of a novel guard plate construction employed in conjunction with the vibratory elements;

Figure 9 is a cross section taken on the line 9—9 on Figure 2, and

Figure 10 is a cross section taken on the line 10—10 on Figure 4.

In the drawings I have illustrated the invention as applied to a safety razor of the well-known Gillette type. It should be understood, however, that the inventive ideas disclosed herein are applicable as well to other types of razors.

In the drawings 1 designates the hollow tubular handle and 2 the head shank with which these handles are usually equipped. For reasons that will become apparent later, the shank 2 is provided with a reduced end extension 3 which may be rotatably mounted in an end of the handle 1 by a simple friction fit or such a fit with an additional pin and slot equipment 4 which will permit a certain degree of relative movement of the shank 25 handle and yet prevent separation thereof. See Figure 2.

The complete handle also includes the usual end head 5 which is likewise provided with a reduced shank 6 which may be securely fixed in the lower end of the handle 1 or rotatably mounted therein according to the particular form of the invention with which the end head is employed.

The head shank 2 is provided with the usual

threaded socket to receive the threaded shank 7 of the clamp head 8, the latter being provided with the usual centering lugs 9 which coact with receiving apertures 10 in the guard plate 11. Thus the clamp head 8 serves to secure in position upon the handle the guard plate 11 and the usual blade 12 interposed between the guard plate and the clamp head. The shaving head hereinafter referred to, and 10 which is removably mounted upon the handle through the medium of the threaded shank 7 and the threaded receiving bore, comprises the clamp head 8, the guard plate 11 and the blade 12.

15 It will be recognized that all of the parts hereinbefore described are parts provided in the conventional type of razor above referred to, the single exception residing in the rotatable mountings for the head shank 2 and the 20 end head 5.

In order to provide for the shock absorbing feature which forms an object of my present invention I provide a shock absorber button 13 mounted on a cross pin 14 movable in 25 apertures provided in the handle 1 adjacent the upper end thereof as illustrated in Figure 1. The button 13 is positioned on the outside of the handle and spaced a suitable distance from the adjacent wall of the handle. It is normally held in that position by a spring 15 coiled about the cross pin and acting between an inner wall of the handle and a head or washer 16 in tending to force the washer against the opposite wall of the handle.

35 In utilizing this shock absorbing principle of my invention, the shaving head and the handle are moved relatively so that the button 13 is projected from the handle transversely of the proposed shaving edge and in a 40 direction away from the surface to be shaved. Thus when the shaver grasps the razor handle adjacent its lower end between the thumb and fingers other than the forefinger he may rest the forefinger upon the button and thus 45 place the spring 15 under light tension. The resilient button equipment thus forms a resilient support for or resistance to the shaving action.

It will be readily understood that with the 50 razor thus held with a bit of energy stored up in the spring 15 the shaving edge will be permitted to automatically follow the uneven contours of the shaving surface with a yielding pressure permitting the head to 55 readily absorb shocks incident to the passing over of partial obstructions such as moles or similar face projections.

By moving the shaving head and the handle 60 relatively so as to position the resilient element 13 to project in a direction paralleling the shaving edge, the handle may be grasped at this point between the forefinger and thumb, with the thumb or forefinger engaging 65 the resilient element. With the parts thus positioned this resilient support for the

razor serves to impart a slight vibration to the shaving head which greatly facilitates the shaving act. The user of the razor may, by properly manipulating the resilient support between the thumb and forefinger, impart to the shaving head a rhythmical vibrating movement, thus increasing the efficiency of the shaving edge in accomplishing the shaving function.

By reason of the provision of the means 75 enabling the relative movement of the shaving head and handle about the axis of the handle it is possible to position the resilient element so that it will project in the position found most efficient in the accomplishment 80 of the functions above described.

In Figure 1 I have illustrated the resilient element projected in a direction for effecting the shock absorbing function, and in Figure 2 is illustrated the positioning of the resilient element for accomplishment of the 85 shaving head vibrating function.

The resilient element may be constructed and mounted in many different ways and in Figures 2 through 7 I have shown some examples of these modifications. In these figures the razor handle alone is disclosed and it will be readily understood that the nature of the invention as thus far described is such that these handles may be manufactured and sold for use as substitutes for standard types of handles now in use. In other words the complete razor or the handle only may be manufactured and sold.

In Figure 2 the resilient element may be 100 in the nature of a resilient rod or wire 17 secured in any suitable manner to the end head 5 and extending longitudinally in the hollow handle to a position adjacent the upper end thereof where it is bent at a right angle and extended through an arcuate slot 18 provided in the handle, said extended end 105 serving to carry the button or head 19 to be engaged by the hand of a user of the razor. The arcuate slot, in combination with the 110 rotatable mounting for the end head 5, will effectively provide for the desired adjustment of position of the button 19.

In Figure 3 the resilient element is in the 115 form of a cross pin 20 mounted in and extended through apertures in the handle and equipped at each end with a head or button 21. A washer 22 is secured in any suitable manner to the center of the cross pin, and a spring 23 is coiled about the pin at each side of the washer for engaging the washer and the adjacent handle wall in a manner for resiliently holding the washer centrally within the bore of the handle.

In Figure 4, the resilient element is in the 125 form of a rod or wire 24 secured at one end to a sleeve 25 fitted in the lower end of the handle and having its other end extended to a point adjacent the upper end of the handle and there angle bent and extended through 130

an aperture in the handle, said extended end being equipped with an engaging head 26. The free end of the member 24 passes through a sleeve 27 fitted in the handle and serving as a mounting means for a coil spring 28 which engages the sleeve and the rod 24 passing therethrough so as to resiliently hold the rod with the head 26 thereof suitably spaced from the outer wall of the handle.

10 In Figure 5 the resilient element also takes the form of a rod or wire 17 secured to the end head 5 and bent at its free end to provide a hump projection 29 extended through a slot 30 provided in the handle and thus serving as a resilient projection for engagement by the hand of the user.

15 In Figure 6 the resilient member is shown in the form of a leaf spring 31 mounted wholly on the outside of the handle and adjustably secured by an axial rivet or other connection 32 at the end of the end head 5, the free end of the spring being extended along the outer wall of the handle in suitably spaced relation to be engaged by the 20 hand of a user for purposes hereinbefore described.

25 In Figure 7 I have illustrated still another form of resilient element in the nature of a spring rod 33 secured to the handle by a band 34 encircling the handle adjacent its lower end, the free end of the rod being extended along the outer wall of the handle to a point adjacent the upper end thereof where it is spaced from the handle to provide the desired resilient support for engagement by the 30 hand of the user.

35 In Figure 8 I have illustrated a novel form of guard plate adapted for use in connection with the resilient elements hereinbefore described and which is provided with guard teeth having their edges angle cut as at 40 so as to engage and deflect the hairs being shaved from an erect to an angled relation to the cutting blade thereby facilitating 45 the shaving act. These teeth are preferably arranged in two sets, the angles of which are oppositely directed so that when the guard plate teeth are drawn over the face of a shaver they will engage the skin 50 and impart thereto a stretching tendency which further facilitates the shaving action in addition to stimulating and massaging the skin.

55 In the drawings I have disclosed the resilient element as mounted adjacent the upper end of the handle. Obviously, however, this element may be similarly mounted nearer the lower end or at any position along the handle which might be dictated by the 60 demands of the buying public.

65 In the foregoing description I have disclosed a simple form of resilient razor support which will serve to absorb shocks incident to the shaving act and thereby facilitate shaving. I have also disclosed means

70 whereby the resilient supporting devices may be employed to impart a slight vibratory movement to the shaving head which will also contribute to the efficiency of the shaving act, and in addition to this feature I have disclosed a novel guard plate which serves to position the hairs being shaved in a manner facilitating the severance thereof and for stretching the skin being shaved, thereby cooperating with the vibratory function in providing a good clean shave.

75 From the foregoing description taken in connection with the accompanying drawings, it is thought that the novel details of construction, the manner of use and the advantages of my invention will be readily apparent to those skilled in the art to which it relates.

I claim:

80 1. A razor handle comprising, a hollow shank, a razor head on said shank, said shank having a cross aperture, a cross pin movable in the aperture and having an engaging head extended a distance laterally beyond the outer wall of the shank engageable simultaneously with the shank and by a finger of the same hand of the user which grasps the shank, and means within the shank to resiliently hold the cross pin head extended so that the hand will cooperate with the 85 surface being shaved to tension said element.

90 2. A razor handle comprising, a hollow shank, means for effecting attachment with a razor head, said shank having a cross aperture, a resilient rod secured at one end within the shank and having its free end extended along within the shank and bent to project through the aperture, said rod being engageable simultaneously with the shank and by a finger of the same hand of the user which engages the shank.

95 3. In a razor, in combination with a cutting blade, a guard therefor, teeth on said guard substantially perpendicular to the longitudinal axis of the guard and blade, said teeth being angularly bevelled from the diagonally opposite front corners of a tooth to the opposite edge.

100 4. In a razor, a handle and a shaving head inflexibly carried thereby, a resiliently mounted shock-absorbing element carried by and projecting beyond one side of the handle between the free end of the handle and said shaving head, said element being adapted for movement substantially radially of the axis of the handle.

105 5. In a razor, a handle, a shaving head inflexibly attached thereto, and a resilient shock-absorbing element on the handle extending generally longitudinally of the handle, said element having a free end yieldable radially of the longitudinal axis of the handle between said head and the free end of the handle.
